UNITED STATES PATENT OFFICE.

WILLIAM CYBEO, OF BOSTON, ASSIGNOR TO JAMES W. TUFTS, OF MEDFORD,
MASSACHUSETTS.

DESIGN FOR CASING OF SODA-WATER APPARATUS.

Specification forming part of Design No. **7,193**, dated February 24, 1874; application filed February 9, 1874.
[Term of Patent 14 years.]

To all whom it may concern:

Be it known that I, WILLIAM CYBEO, of Boston, in the county of Suffolk and State of Massachusetts, have invented and produced a new and original Design for the Casing of a Soda-Water Apparatus, of which the following is a full, clear, and exact description, reference being had to the accompanying photograph, making part of this specification.

In the photograph, A represents the body or main portion of the casing of a soda-water apparatus, which is of rectangular form. From the top of the portion A rises a spire, B, the

design thus produced being unique and ornamental.

What I claim as my invention, and desire to secure by Letters Patent, is—

The design for the casing of a soda-water apparatus, substantially as herein shown and described.

Witness my hand this 4th day of February, A. D. 1874.

WILLIAM CYBEO.

In presence of—

P. E. TESCHEMACHER,
EDWIN BOWKER.
